UNITED STATES PATENT OFFICE.

OCTAVIAN G. I. O'HEIR, OF LOWELL, MASSACHUSETTS.

SHIRT ATTACHMENT.

Application filed January 8, 1925. Serial No. 1,184.

This invention relates to shirts such as are worn by men, and its purpose is to prevent the skirts from crawling up where the wearer is engaged in more or less active exercise, and particularly where a belt is worn.

Its purpose is generally to keep down the bottom of a shirt, and by skirt in this specification, I mean to include any shirt like garment such, for instance, as a shirt waist.

In the drawings, Fig. 1 is an elevation of a shirt, of the open front type, opened showing my device in place.

Fig. 2 is a front elevation showing the lower part of a shirt, with the legs of the wearer indicated.

Fig. 3 is a rear elevation similar to Fig. 2.

Fig. 4 is a side elevation with parts of 20 the shirt broken away to show the way it is attached.

Fig. 5 is a detail on an enlarged scale showing a band in place.

Fig. 6 is a front view of the shirt buttoned up, with the front skirts removed and indicated by dotted lines.

Fig. 7 is a detail of a preferred form of attaching loop.

Fig. 8 is a detail of paralleled slits forming a passage which takes the place of a loop.

Fig. 9 is a detail of part of a band without the enlarged portion.

Fig. 10 is a modification.

In the drawings, A represents the buttocks, B, B, the legs of the wearer, and S represents the shirt as a whole, while M represents one of my bands.

The shirt S, as shown, is open at the front 14, which is closed when in use, by suitable buttons 17. It is split at the lower part on each side at 15 and 16, forming the rear skirt 12 and the front bifurcated skirts, 10 and 11.

In positions on the inside of the skirts 10, 11 and 12, where they will be near the upper part of the thigh of the wearer, are loops. The loops 22 and 23 are inside skirt 11 and the loops 20 and 21 inside skirt 10.

The loops 24, 25, 27 and 26 are inside skirt 12.

My preferred form of band M includes a

fairly broad elastic middle portion 30 which may be made of rubber webbing, at each end of which is an enlarged portion 31 or 32, the purpose of which is to serve as a stop and keep it from readily slipping through the loops, but of permitting it to be drawn through when the band is being put in place, as for instance after the shirt has been laundered.

At each end of the enlarged portions 31 and 32 is a tying string 33 or 34 by which the ends can be brought together.

There are preferably two of these bands, 65 in each of which the elastic middle part is passed through loops 23, 24, 25, or 21, 26, 27, or it may pass through four loops, in any event bringing an enlarged part or stop 31 or 32 in such position outside of 70 different loops that it will be held in position when the shirt is removed. As shown in Fig. 5 the string 34 is passed through loop 22.

As shown in Fig. 4 the ends 33 and 34 are 75 brought around the leg near the top of the thigh, and tied, preferably in a bow knot.

The result of this is that when the wearer bends, or when for any other cause the skirts tend to lift they will be brought back 80 by the elasticity of the part 30 and will always return to position.

Each loop such as 23 may be a separate piece of material attached by sewing 40 and 41, whereby a passage is formed, or as 85 shown in Fig. 8 a passage may be formed by making two parallel slits 51 and 52 in a skirt 50, through which a band M may be passed.

As shown in Fig. 9 the band may be made 90 without any enlarged portions, the elastic part 60 terminating at each end in a tying string 61.

It is also obvious that the whole band such as M could be elastic if desired, or it could 95 all be non-elastic.

The tapered end 62 of 60 serves as a stop if the loop 64 is attached to shirt 63 by stitching 65 and 66 which is close enough together to prevent 60 from passing, but far 100 enough apart to allow string 61 to pass.

As shown in Fig. 10, a single loop 70 attached to shirt 71 might be used and a band 72 of uniform material and size might be

removably passed through it. Band 72 might be elastic or inelastic and loop 70 might be elastic or inelastic.

If band 72 is inelastic and loop 70 is elastic, its elasticity will bring the shirt back in place but it will not be as durable as an inelastic loop on account of laundering.

I claim:

1. The combination with a shirt having 10 skirts in which are inside on each side a plurality of loops forming passages; of two bands each of which passes through a plurality of loops and each of which is formed of a central elastic portion which terminates at each end in an enlarged portion and a 15 tying string which extends beyond each of said enlarged portions.

2. The combination with a shirt having skirts in which are on each side a plurality 20 of loops forming passages; of two bands each of which passes through a plurality of loops and each of which is formed of a central elastic portion which terminates at each

end in an enlarged portion and a tying string which extends beyond each of said 25 enlarged portions.

3. The combination with a shirt having skirts in which there are on each side, inside, a plurality of loops forming passages; of two bands each of which passes through a plurality of loops and each of which is formed of an elastic central portion which terminates at each end in a stop to hold 30 each band in position with relation to said passages and a tying string.

4. The combination with a shirt having skirts in which there are on each side a plurality of passages; of two bands each of which passes through a plurality of passages and each of which is formed of a central portion which terminates at each end in a stop to hold each band in position with 35 relation to said passages and a tying string of less width than the central portion.

OCTAVIAN G. I. O'HEIR.
